UNITED AUTOGRAPHIC REGISTER CO., OF CHICAGO, ILLINOIS, A CORPORATION OF
ILLINOIS

MULTIPLE-WOUND-ROLL STATIONERY AND METHOD OF USING SAME

Application filed September 30, 1924. Serial No. 740,869.

This invention relates most particularly to a form of stationery which is to be used in such machines as manifolding typewriters. I have shown the stationery which embodies the features of my invention as having been applied to a typewriter of the type in which the entire typewriter body and operating mechanism moves with relation to the platen when the apparatus is operated, as well as having shown it as applied to a typewriter of the type in which the platen carriage moves relatively to the body and other operating portions.

In the forms of multiple copy stationery which have heretofore been employed, such as the commonly used many roll type, the fan fold or the superfold type, many objections are encountered. In the form in which many rolls are employed, each roll containing but one web or sheet, the work imposed upon a relatively delicate and easily operated mechanism, such as a typewriter, is too much because each roll has to receive a pull in order to unwind it, such a pull on each roll occurring simultaneously with that on each of the others. Another objection lies in the increased labor involved in having to load many single wound rolls, each roll involving a separate and duplicate operation. This objection is further increased by reason of the more elaborate and bulky mechanism which is necessary to accommodate the many separate single wound rolls. Further objection to the single wound roll form of stationery is that the sidewise shifting of the separate webs is quite marked and results in transverse misalignment of the forms printed thereon. Additional objection is found to the single wound form of roll stationery because the smaller sizes of roll will produce a very objectionable tendency of the individual sheets to curl. Increased objection may also be experienced in the single wound form of roll stationery because of the tendency of the several superposed sheets to cling to each other, thus rendering the operation of aligning the several forms difficult, this tendency being created by reason of the necessity of having to bring a tension to bear upon each web in order to unwind its individual supply

roll sufficiently, thus causing the superposed webs to be pressed or drawn closely together.

As objections to the fan and superfold styles of stationery may be mentioned the poor stacking which is accomplished by such forms. In addition to the instability thus created, the spaces left at the folds permit dust and light to enter at the edges of the webs, thus soiling as well as rotting the paper. Another objection is that wind may readily play havoc with the usual folded style of stationery by displacing it from the stack. Further objection to the folded style is the formation of creases which frequently catch in portions of the apparatus and become torn, or which, because of such creases, result in destruction of carbon paper. Additional objection is found in fan fold stationery because of the necessity of having to use wide sheets in the preparation of such stationery. In all wide sheets of paper there is considerable stretch at the edges and frequently one edge is longer than the other, thus throwing the sheet out of alignment in the printing press. This produces poor alignment of printed forms when the fan fold is made.

With these many objections in mind it will become much more apparent as to the features of novelty involved in the invention I have disclosed herein.

An object of my invention is to produce a form of roll stationery for manifolding typewriters, billing machines and the like, in which several superposed duplicate form printed webs are embodied in a novel manner in a unitary bundle which will permit of the accomplishment of aligning operations with the greatest of ease and simplicity.

A further object is to produce a form of stationery which while affording the use of many copies, will not impose excessive conditions of strain upon either the operator or the machine in its handling and use.

A further object is to produce a form of roll stationery which will permit of the use of the simplest of apparatus in its attachment to the machine with which the stationery is to be used.

A further object is to produce a form of roll stationery in which a material saving of

stationery and carbon paper is effected through the elimination of all chance of waste.

These and other objects are attained in the 5 form of roll stationery described in the following specification and illustrated in the accompanying drawing, in which:

Fig. 1 is a perspective view of the typewriter of the type in which the body and operating mechanism is mounted so as to be 10 relatively movable to the platen, with improved roll stationery embodying the multiple wound features of my invention, in position for use therewith.

Fig. 2 is an enlarged view of a detail of the apparatus employed for using my improved stationery.

Fig. 3 is a fragmental perspective view of 20 features of the apparatus I employ in using my improved stationery.

Fig. 4 is a view illustrating certain features of the manner of using my improved stationery.

Fig. 5 is a perspective view of a typewriter 25 of the type in which the platen is movable relatively to the body and operating mechanism, with improved roll stationery embodying the multiple wound features of my invention in position for use therewith.

Fig. 6 is an enlarged view of a detail of 30 the apparatus employed for using my improved stationery.

Fig. 7 is a fragmental perspective view of 35 features of the apparatus I employ in using my improved stationery.

Fig. 8 is a view illustrating certain features of the manner of using my improved stationery.

Fig. 9 is a perspective view of another way 40 in which the multiple wound roll may be supported relatively to a typewriter using this style of stationery.

Fig. 10 is a fragmental side elevation of 45 portions of Fig. 9, showing a somewhat diagrammatic arrangement of the roll webs and other elements.

Fig. 11 is a perspective view along some- 50 what diagrammatic lines, of another way in which my improved roll stationery may be used.

Figs. 12, 13, 14 and 15 are views of details of the apparatus shown in Figs. 9 and 11.

The stationery which I have disclosed herein is produced by winding together upon 55 a single roll as many webs of paper as may be required to obtain the desired number of copies of a record to be made. In the example I have shown a roll of stationery made up of five webs. Each web is provided with 60 the usual aligning sets of aligning apertures 13, the sets which are spaced apart as shown, so as to demarcate or form between adjacent sets of apertures a sheet 14 which may be torn off from each web for use as intended. Suitable devices, such as the aligning pins 15 and

16 are used in the respective forms of typewriter construction shown, to secure alignment of the webs and the forms which are printed thereon, as is usual.

Detailed description of the apparatus and 70 method of alignment will not be given in as much as such apparatus and methods are well known and it is merely the stationery and its use which constitutes the features of novelty herein. Such use involves, however, 75 a novel method of serving the webs, or strips, to the typewriter, or duplicating machine, and attendant guiding and supporting means for the multiple strips.

In the winding of any roll from webbed 80 material the outer convolution of web is naturally of greater circumference than the inner ones. If several webs are wound together, as has been done in the present invention, it is quite evident therefore that the 85 convolution of the outer web will be materially of greater length than the corresponding convolution of the web which occupies the innermost position. For this reason it is therefore apparent that the intermediate 90 webs will produce convolutions of varying lengths. Each web, as has been shown at 13 is punched at uniform intervals and is form printed in uniformly spaced position relatively to the punched apertures. If these several 95 webs are started to be wound into roll form with their punched ends in register, the gradually accumulating convolutions of web will 100 result in the punched ends becoming more and more uniformly out of register or stepped off, see Fig. 12, as the diameter of the roll increases. Therefore when a yard or so of the webs have been unwound from the roll and the several ends or apertures brought together in registration, it will be found that 105 a "drape" is formed in all the webs relatively to one another. This drape in each web increases in length over the preceding out web until the innermost web is reached. It is this feature which is utilized in the using of my 110 improved stationery.

By now bringing the ends together with 115 their apertures in registration it will be found that by placing the outermost web of the roll upon the bottom of the superposed series of webs the drape will assume somewhat the appearance shown in Figs. 1, 4, 5 and 8. I have shown a simple form of rack 17 which is placed in a convenient position as shown, so that proper amount of drape is easily 120 formed with the innermost wound web forming the topmost web on the platen, as in Fig. 1, the intermediate webs forming the corresponding interspersed webs on the platen. With the webs in this position it will be quite 125 easy to accomplish their unwinding from the roll when they are fed over the platen, because the web having the least drape, which is the outermost web 18, will be the only one upon which tension is brought to bear in or- 130

der to draw the webs from the roll. The remaining webs will unwind quite loosely and form their natural and independent drapes as shown. This brings about a condition 5 wherein but one web acts under tension, the remaining webs, which previously were upon the roll quite tightly, having become separated so that they are now free to be moved or shifted independently during any aligning operation. This freedom of movement 10 is brought about by virtue of the cushion of air which is formed between adjacent sheets because of the drape.

In Fig. 5 I have shown a swinging kicker 15 bar 19 which operates to give the web 18 a pull each time the typewriter is operated to present a fresh sheet 14 in position to be aligned with the superposed sheets upon which the copies are to be produced. A roller 20 20 operating upon an inclined track 21 is provided to bring about the web unrolling operation each time the typewriter is shifted to new sheet position. However the particular mechanism illustrated by which this is 25 accomplished is not, per se, a portion of the invention herein described and need not be specifically set forth.

In Fig. 9 I have shown a wall rack 16 which I employ to support the multiple 30 wound roll in an elevated position with relation to the typewriter. This is a convenient form of position because of the fact that a pusher bar 17 is employed instead of the swinging kicker bar 19 shown in the other 35 figures. The operation is fully illustrated by dotted and full lines in Fig. 10.

In Figs. 11, 12, 13 and 14 a form of roll support is shown, which is merely a trapeze as it were. The operation of loading the 40 trapeze is merely to place the trapeze 18 in mounted position with the roll, as shown in Fig. 3, and then to lift the trapeze into swinging position beneath the typewriter as shown in Fig. 11. The webs are then mounted in 45 the typewriter by bringing the ends together and over the small guide rollers to produce the drape shown in Fig. 12 in dotted lines.

From the description given, it will be understood that after the multiple strips are 50 wound upon the roll, the outer or final ends of the strips bear a stepped relation, and that in serving the strips the forms at the outer end are brought into registration, the strips are supported by guiding and supporting 55 means, and the registering forms are brought into the grip of the feeding mechanism (line-spacing mechanism, in the illustration given). The arrangement described provides for the draping effect back of the supporting and 60 guiding means which have been described, and the unwinding of the strips is effected by the shortest outer strip of the group of strips passing from the roll to the supporting and guiding means, which, in the illustration 65 given, is the outer strip on the roll of station-

ery. The forms, or tickets, are uniform in the sense that they are of uniform length. The use of register perforations is also highly important in the method of storing and feeding multiple strips described herein; and it is quite essential that these register perforations be as nearly as possible uniformly spaced longitudinally of the strips. 70

Having thus described my invention what I claim is:

1. The method of storing and serving multiple strips of stationery, said strips comprising tickets of substantially uniform length, which comprises winding a series of said strips on a roll with the outer ends in stepped relation, the outer end of one of the outer strips terminating first, and passing the outer end-portions of the strips about suitable guiding and supporting means and bringing the end tickets into registration and within the grip of the feeding means of a duplicating machine, the portions of the strips between the guiding and supporting means and the roll being permitted to drape in successively increasing loops and the outer strip having 90 the shortest portion intervening between the guiding and supporting means and the roll serving in the operation of unwinding the strips. 95

2. The method specified in claim 1, in which the outer strip employed for unwinding the strips from the roll is the outer strip of the series in the wound condition on the roll.

3. A roll of stationary comprising a multiple wound series of strips having forms of substantially uniform length and register-perforations which are substantially uniformly spaced, the outer end of one of the outer strips of the series terminating first and the outer ends of the other strips being in progressively stepped relation; a support for the roll; a duplicating machine provided with feeding mechanism within the grip of which the forms in registered position are held, said duplicating machine being provided with register-pins into engagement with which the register-perforations of the strips may be brought; and guiding and supporting means spaced from the roll support 105 and engaging the strips between the duplicating machine and the roll, the portions of the strips between the guiding and supporting means and the roll being in draped relation and the outer strip having the shortest 110 length intervening between the roll and the feeding mechanism of the duplicating machine serving as a means for effecting unwinding of the roll. 115

4. In combination: a multiple-wound roll stationary consisting of a plurality of webs wound in superposed relation in a single roll, each of said webs having sets of printed forms thereon spaced apart substantially uniformly, the webs being so wound that the forms 120

register substantially at the beginning of the roll and the webs terminate in stepped relation at their outer ends; a support for the roll; duplicating mechanism; and web-supporting and guiding means associated with said mechanism and spaced from said roll-support, said webs and duplicating mechanism being provided with co-acting aligning means, and said webs extending from the roll over said supporting and guiding means and into the grip of said duplicating mechanism, the portions of said webs between the roll and web-supporting and guiding means being draped in successively increasing loops.

5. In combination: a multiple wound roll stationery comprising a plurality of webs wound in superposed relation into a roll, each of said webs having forms thereon at uniform distances, the first forms at the inner end of the roll being in substantial registration and the outer ends of the webs bearing a stepped relation; a roll-support carrying said roll; duplicating mechanism equipped with aligning means co-acting with aligning means at the outer ends of the webs, the forms at the outer ends of the webs being brought into registration; and roll-supporting and guiding means associated with said duplicating mechanism and spaced from the roll-support, the portion of the webs between the roll-support and said web-supporting and guiding means being draped in successively enlarged loops and the shortest outer web serving as a means for effecting unwinding of the roll.

6. In combination: a multiple wound roll stationery comprising a plurality of webs having printed blank forms thereon at regular intervals and each form having aligning perforations, said perforations being uniformly spaced longitudinally of the webs, said webs being wound on the roll so that the first forms of the webs substantially coincide at the beginning of the roll and the outer ends of the webs bear a stepped relation; a roll-support carrying said roll; duplicating mechanism; web-supporting and guiding means associated with said duplicating mechanism and spaced from the web-supporting roll; and aligning means associated with the duplicating mechanism engaging the aligning perforations of the forms at the outer ends of the webs, the portions of the webs between the roll-support and said web-supporting and guiding means being draped in successively enlarged loops, for the purpose set forth.

7. In combination: duplicating mechanism and associated register-pins; web-guiding and supporting means associated with said mechanism; a roll support spaced to permit draping of webs between it and said web-guiding and supporting means; and a roll of stationery comprising a multiple wound series of strips having forms of substantially

uniform length and register-perforations which are substantially uniformly spaced longitudinally of the strips, the outer end of one of the outer strips of the series terminating first and the outer ends of the other strips being in progressively stepped relation, the end forms of the strips being entered in the duplicating mechanism and brought into registration by engaging the register-perforations with the register-pins, the portions of the strips between the web-guiding and supporting means and the roll support presenting loops of progressively increasing sizes.

8. The method of serving strips from a multiple wound roll comprising tickets of substantially uniform length provided with register-perforations which are substantially uniformly spaced longitudinally of the strips, which comprises providing the end- portions of the strips with loops of successively increasing sizes, and bringing the end forms into registration and within the grip of the duplicating mechanism through which the strips are to be fed.

In testimony whereof I have hereunto affixed my signature.

ALPHONSE E. IMBUS.
